UNITED STATES PATENT OFFICE.

JOHN WILLIAM JONES, OF CANNOCK, ENGLAND, ASSIGNOR TO HASLAM & STRETTON
LIMITED, OF CARDIFF, WALES.

MINER'S ELECTRIC SAFETY-LAMP.

1,373,820.

Specification of Letters Patent. Patented Apr. 5, 1921.

Application filed May 10, 1920. Serial No. 380,328.

To all whom it may concern:

Be it known that I, JOHN WILLIAM JONES, a subject of the King of Great Britain and Ireland, residing at Wave Crest, Blackfords, 5 Cannock, Staffordshire, England, have invented certain new and useful Improvements Relating to Miners' Electric Safety-Lamps, of which the following is a specification.

This invention relates to miner's electric 10 safety lamps and has for its special object to provide a flash lamp of a simple and light form suitable for the use of colliery officials, the lamp being provided of such a form that it can be carried in the pocket or be attached 15 to a belt by means of a hook, or be carried in any other suitable way.

The invention comprises the construction which is hereinafter described.

The invention is illustrated by way of 20 example in the accompanying drawings in which—

Figure 1 is a vertical section of a lamp constructed according to the invention.

Fig. 1^a is a detail cross section in a plane 25 transverse to the plane of the section Fig. 1.

Fig. 2 is an under plan of the top part of the lamp, and

Fig. 3 is a plan view of the bottom part or casing carrying the cell.

As illustrated in the accompanying drawings the top part of the lamp is provided as 30 a cylindrical casing *a* at the top of which there is mounted a bull's eye lens *b*. An annular groove *b*¹ is provided for the reception 35 of a jointing ring of rubber or other suitable material *b*² which is mounted within the annular groove *b*¹ so as to protrude slightly and thus to make a tight joint with the cylindrical casing *a*.

The cylindrical casing is at its upper edge 40 inwardly diverted at *a*¹ for the retention of the lens *b* in position and means are provided such as the formation of an inwardly protruding ridge at *a*² on the cylindrical casing *a* by means of which the lens *b* may be supported.

Beneath the lens *b* the lamp bulb *c* is mounted. This is carried within a socket *c*¹ carried by an arm or fitting *c*² secured to the 50 contact plate *d*. The plug *c*⁴ of the lamp bulb is screw threaded for insertion within the screw threaded bore of the socket *c*¹ and the lower end of the plug *c*⁴ engages the contact *e* which is supported upon a spiral 55 spring *f*, the lower end of which is secured

to the central contact *g* mounted beneath the contact plate *d*, the spring *f* being advantageously secured in position by a screw *h* by which the contact *g* is thus also held in its position within a recess of corresponding 60 form on the under side of the contact plate *d*. The second contact *i* is formed as a bushing and is fitted in a recess of corresponding form in the contact plate *d* and a screw *i*¹ serves to secure an upstanding contact plate *j* to the contact *i*.

The contact plate *d* is carried within a cylindrical fitting *k* mounted within and secured at the lower end of the cylindrical casing *a*. This cylindrical fitting *k* has at its 70 upper end an inwardly extending flange *k*¹ for the retention of the contact plate *d* and the lower part of the inner face of this fitting is screw threaded for the reception of a retaining ring *l* by which the contact plate 75 *d* may be held within the cylindrical fitting *k*.

At the lower end of the cylindrical casing *a* a lug *m* is provided having a hole *m*¹ adapted to come into register with a similar 80 hole *n*¹ in a similar lug *n* secured at the upper end of the casing or container *o* of the cell *p* so that thus a lead rivet *q* may be introduced through the aligned holes *m*¹ *n*¹ for locking the casing or container *o* to the top 85 of the lamp. A switch *r* may be provided on the casing *a* and operable by a pin or plug *r*¹ upon the outwardly protruding end of which a button *r*² is mounted so that thus contact may be made with the upstanding 90 contact or plate *j* by causing the pin or plug *r*¹ to move inwardly. The construction of the cell *p* and the casing or container *o* may be similar to that described in the specification filed pursuant to the co-pending application No. 316,792, dated 11th August, 1919, which has matured into Patent 1,352,636, dated Sept. 14, 1920.

It will be understood that current may pass from the cell through the contact *g*, the 100 spiral spring *f* and the plug of the lamp bulb, thence through the filament of the lamp through the socket *c*¹ and the fitting *c*², the casing *a* and the contact plate *j* and the second contact *i*, when the switch *r* is closed. 105

I claim:

1. An electric safety flash lamp, consisting in combination of the cylindrical casing of the lamp top, a lens surmounting and carried by the said cylindrical casing, a con- 110

tact plate within the said cylindrical casing, said contact plate carrying a centrally disposed contact and a laterally disposed contact plate, a transversely disposed fitting 5 within the said cylindrical casing, said fitting being supported at its respective ends upon the said contact plate, a lamp bulb carried centrally in the said transversely disposed fitting, and a switch on the said 10 cylindrical casing operable from outside and adapted to complete the circuit by contact with the upstanding contact plate aforesaid, substantially as described.

2. An electric safety flash lamp, consisting in combination of the cylindrical casing 15 of the lamp top, a lens surmounting and car-

ried by the said cylindrical casing, a contact plate within the said cylindrical casing, said contact plate carrying a centrally disposed contact and a laterally disposed contact 20 plate, a transversely disposed fitting within the said cylindrical casing, said fitting being supported at its respective ends upon the said contact plate, a lamp bulb carried centrally in the said transversely disposed 25 fitting, a switch on the said cylindrical casing and comprising a sliding member operable from outside, said switch being adapted to complete the circuit by contact with the upstanding contact plate aforesaid, sub- 30 substantially as described.

JOHN WILLIAM JONES.
